Primary Examiner — Mary Ann Calabrese*Assistant Examiner* — Catherine Ho(74) *Attorney, Agent, or Firm* — Tucker Ellis LLP; Carlos Garritano(57) **CLAIM**

The ornamental design for an inventory management apparatus, as shown and described.

DESCRIPTION

FIG. 1 is a perspective view of an inventory management apparatus, showing my new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines in the drawings illustrate the portions of the inventory management apparatus that form no part of the claimed design.
